SELF CLOSING SAFETY FILLING CAP

Filed May 27, 1926

Patented May 10, 1927.

1,628,519

UNITED STATES PATENT OFFICE.

JOHN ALBERT SHOUP, OF BATTLE CREEK, MICHIGAN.

SELF-CLOSING SAFETY-FILLING CAP.

Application filed May 27, 1926. Serial No. 112,174.

This invention relates to a novel cap for liquid containers such as oil cups, automobile radiators, crank cases and gasoline storage tanks, and the like, and has for one of its objects to provide a device of this character which will prevent the entrance of dust and other foreign matter into the container, which to permit the container to be filled, may be readily opened through the medium 5 of the spout of an oil can or water bucket or the nozzle of the filling hose of a gasoline dispensing station and the like, and which will automatically close immediately after the withdrawal of the spout or nozzle.

10 With the foregoing and other objects in view, the nature of which will become apparent as the description proceeds, the invention consists of the construction, combination and arrangement of parts hereinafter 15 fully described and claimed, and illustrated in the accompanying drawing, wherein:

Figure 1 is a sectional view taken on a plane extending vertically and centrally through the cap,

20 Figure 2 is a sectional view taken on the vertical plane indicated by the line 2-2 of Figure 1,

Figure 3 is a sectional view taken on the horizontal plane indicated by the line 3-3 25 of Figure 1, and

Figure 4 is a similar view taken on the horizontal plane indicated by the line 4-4 30 of Figure 1.

Corresponding and like parts are referred 35 to in the following description, and designated in the several views of the accompanying drawing, by similar reference characters.

The cap comprises a hollow cylindrical body 1 which is closed at its upper and 40 fully open at its lower end. The body 1 is provided at its lower end with a laterally offset and internally screw threaded flange 2 to permit of its attachment to an oil cup, automobile radiator, automobile crank case, 45 automobile gasoline storage tank or the like. The offsetting of the flange 2 from the body 1 provides a horizontal shoulder 3. The top 4 of the body 1 extends laterally beyond the latter, and is provided with an upwardly and laterally extending projection or lip 5 which has a concave under face 6. A filling opening 7 which extends vertically 50 and longitudinally thereof, is formed in the body 1 immediately below the extension 6. The vertical dimension of the opening 7 is less than the corresponding dimension of the body 1, and such opening is located in the upper portion of the body. A hollow cylindrical valve 8 which is open at its upper 55 and closed at its lower end, is slidably arranged within the body 1, and is adapted to occupy a closed or an opened position with respect to the body. When the valve 8 is in closed position, it extends over the filling 60 opening 7, and a flange 9 projecting from its bottom 10 is in contact with the under side of the shoulder 3. When the valve 8 is in opened position, the filling opening 7 is uncovered and the flange 9 is spaced below the 65 shoulder 3. The valve 8 is yieldingly retained in closed position by a spring 11 which is mounted upon a rod 12 between a seat 13 bearing against the under side of the bottom 10 of the valve and a seat 14 70 resting upon a nut 15 adjustable on the rod. The rod 12 is secured to and depends from a bar 16 which is arranged within and extends diametrically of the body 1 and valve 8 and is secured as at 17 to the body. The 75 upper end of the rod 12 passes through the bar 16 and is secured to said bar by nuts 18 carried by the rod and contacting with the upper and lower sides of the bar. The bottom 10 of the valve 8 is provided with an 80 opening 19 for the reception of the rod 12, and the lateral side of the valve 8 is provided with longitudinally and vertically extending slots 20 for the reception of the ends of the bar 16. The seats 13 and 14 are 85 loose on the rod 12, and the nut 15 may be adjusted to vary the tension of the spring 11. The lateral side of the valve 8 is provided with ports 21 through which the liquid flows 90 into the container when the valve 8 is in opened position and which are located wholly within and closed by the body 1 when the valve is in closed position. A sleeve 22 surrounds the body 1 and is secured to the valve 8 by a screw 23. The axial dimension of the 95 sleeve 22 is less than the corresponding dimension of the valve 8 and body 1, and said sleeve is adapted, when the valve is closed, to occupy a position upon the upper portion of the body 1 over the filling opening 7. The screw 23 passes through the filling opening 7. The sleeve 22 is provided directly below the extension 5 with an upwardly and laterally projecting extension 24 which is provided with a concave upper face 25 and 100 with openings 26. The extension 24 provides an element through the medium of which

the valve 8 may be readily depressed or moved into opened position, and the openings 26 are provided for the purpose of maintaining the upper surface of said elements free of moisture.

From the foregoing and accompanying drawing, it should be apparent that the valve 8 is normally held in closed position by the spring 11, and that when the valve 8 is in closed position the filling opening 7 is covered by the lateral side of the valve and the sleeve 22 and the ports 21 of the valve are closed by the lateral side of the body 1 and the flanges 2 and 9. When it is desired to fill the container in connection with which the cap is used, the spout of the oil can or water bucket or the nozzle of the filling hose of a gasoline dispensing station is positioned between the extensions 5 and 24 and downward pressure exerted on the extension 24. The spout or nozzle may be readily positioned between the extensions 4 and 24 due to the fact that the opposing surfaces 6 and 25 of these parts are arranged in divergent relation. Pressure exerted on the extension 24 will move the valve 8 downwardly with respect to the body 1 and against the tension of the spring 11, with the result that the filling opening 7 and ports 21 are uncovered, and with the result that the liquid poured into the opening 7 will readily flow through the ports 21 into the container. The downward movement of the valve 8 is limited by the top walls of the slots 20 and bar 16 and by the bottom wall of the filling opening 7 and screw 23. When the pressure is removed from the extension 24, the spring 11 will react and move the valve upwardly, with the result that the filling opening 7 and ports 21 will be closed. When the valve 8 is in closed position, dust and other foreign matter cannot enter the container, and the valve will be returned rapidly to closed position immediately after the withdrawal of the pressure from its extension 24.

It should be understood that the drawing is merely illustrative and does not pretend to give exact proportions. Furthermore, the said drawing is illustrative of a preferred construction, it being my expectation that various changes and modifications may be made without departing from the spirit and scope of my invention.

What is claimed is:—

1. A cap for liquid containers, comprising a hollow body closed at its upper end and open at its lower end and provided in its side with a filling opening, a hollow valve 50 slidably arranged within the body and closed at its lower end and provided in its side with a port, a spring normally supporting the valve within the body to permit the valve to close the filling opening and the body to close the port, and an element located out-

wardly of the body and connected to the valve and adapted to permit the valve to be moved downwardly against the tension of the spring to uncover said opening and port.

2. A cap for liquid containers, comprising a hollow body closed at its upper and open at its lower end and provided in its side with a filling opening, a hollow valve slidably arranged within the body and provided in its side with a port, a spring normally supporting the valve within the body to permit the valve to close the filling opening and the body to close the port, and an extension carried by each of the valves and body, said extensions being closely related so and having divergent opposing surfaces and adapted to permit the valve to be moved downwardly against the tension of the spring to uncover said opening and port.

3. A cap for liquid containers, comprising a hollow body closed at its upper and open at its lower end and provided in its side with a filling opening, a hollow valve slidably arranged within the body and open at its upper and closed at its lower end, said valve being provided in its side with a port, a rod carried by the body and extending through the bottom of the valve, and a spring supported by said rod and contacting with the bottom of the valve and adapted to hold the valve within the body to permit the valve to close the filling opening and the body to close the port.

4. A cap for liquid containers, comprising a hollow body closed at its upper and open at its lower end and provided in its side with a filling opening, a hollow valve slidably arranged within the body and closed at its lower and open at its upper end and provided in its side with a port and with slots, a bar secured to the body and passing through said slots, a rod secured to and supported by the bar and passing through the bottom of the valve, and a spring supported upon the rod and contacting with the bottom of the valve to normally hold the valve within the body to permit the valve to close the filling opening and the body to close the port.

5. A cap for liquid containers, comprising a hollow body closed at its upper and open at its lower end and provided in its side with a filling opening, a hollow valve slidably arranged within the body and provided in its side with a port, a spring normally holding the valve within the body to permit the valve to close the filling opening and the body to close the port, a sleeve surrounding the body and connected to the valve, and an extension carried by the sleeve to permit the valve to be lowered with respect to the body.

6. A cap for liquid containers, comprising a hollow body closed at its upper and open at its lower end and provided in its side with a filling opening, a hollow valve slidably ar-

ranged within the body and provided in its side with a port, a spring normally supporting the valve within the body to permit the valve to close the filling opening and the body to close the port, an extension carried by the top of the body, a sleeve surrounding the body and connected to the valve, and an extension carried by the sleeve, said ex-

tensions being closely related and having divergent opposing surfaces and adapted to permit the valve to be moved downwardly against the tension of the spring to uncover said opening and port.

In testimony whereof I affix my signature.

JOHN ALBERT SHOUP.
